UNITED STATES PATENT OFFICE

115,304

DESIGN FOR A STORE FRONT

Harry L. Wyman, Minneapolis, Minn.

Application July 29, 1938, Serial No. 78,952

Term of patent 7 years

To all whom it may concern:

Be it known that I, Harry L. Wyman, a citizen of the United States and residing in the city of Minneapolis, county of Hennepin, and State of Minnesota, have invented a new, original, and ornamental Design for a Store Front, of which the following is a specification, reference being had to the accompanying drawing, forming a part thereof, wherein,

Fig. 1 is a perspective view of a store front showing my new design; and

Fig. 2 is a top plan view of the same on a greatly reduced scale.

I claim:

The ornamental design for a store front, substantially as shown.

HARRY L. WYMAN.
